UNITED STATES PATENT OFFICE

124,604

DESIGN FOR A BUCKLE BODY

Earl H. Goodwin, Swampscott, Mass.

Application September 13, 1939, Serial No. 87,189

Term of patent 7 years

To all whom it may concern:

Be it known that I, Earl H. Goodwin, a citizen of the United States, residing at Swampscott, in the county of Essex and State of Massachusetts, have invented a new, original, and ornamental Design for a Buckle Body, of which the following is a specification, reference being had to the accompanying drawing, forming part thereof.

In the drawing,

Fig. 1 is a plan view of a buckle body showing my new design;

Fig. 2 is a side elevation of the buckle body;
Fig. 3 is an end elevation looking to the right of Fig. 2; and

Fig. 4 is a section taken on line 4—4 of Fig. 1.

I claim:

The ornamental design for a buckle body, substantially as shown.

EARL H. GOODWIN,
